DISPENSING CAP FOR A CONTAINER

Alvin J. Porter, Minneapolis, Minn., assignor to Product Design & Engineering, Inc., Minneapolis, Minn., a corporation of Minnesota

Filed July 29, 1968, Ser. No. 12,937

Term of patent 14 years

Int. Cl. D9—02

U.S. Cl. D9—258

FIG. 1

FIG. 2

FIG. 3

FIG. 4

FIG. 1 is a top plan view of a dispensing cap for a container, showing my new design.

FIG. 2 is a side elevational view thereof.

FIG. 3 is a side elevational view rotated ninety degrees from that of FIG. 2.

FIG. 4 is a side elevational view rotated ninety degrees from that of FIG. 2 in a direction opposite to that of FIG. 3.

I claim:

The ornamental design for a dispensing cap for a container, as shown.
